SAMUEL STRAUS, OF NEW YORK, N. Y.

PULL-SOCKET FOR ELECTRIC LAMPS.

1,253,296.

Specification of Letters Patent. Patented Jan. 15, 1918.

Application filed June 3, 1916. Serial No. 101,446.

To all whom it may concern:

Be it known that I, SAMUEL STRAUS, a Russian subject, residing in the city, county, and State of New York, have invented certain new and useful Improvements in Pull-Sockets for Electric Lamps, of which the following is a specification.

My invention relates to pull sockets for electric incandescent lamps and has for its object to provide an improved and simplified construction for such sockets requiring but a small number of simple and easily formed parts which can be quickly and inexpensively assembled. Another object of my invention is to provide a socket, as just stated, which shall be little liable to get out of order and which shall be certain in its operation.

My invention resides in the special features of construction and combination of parts as hereinafter described.

My invention will be better understood by referring to the drawings in which Figure 1 is an axial section, through the plane which includes the chain and chain funnel, taken along the line 1—1 of Fig. 3; Fig. 2 is an axial section taken along the line 2—2 of Fig. 3; Fig. 3 is a plan view of Fig. 1, looking from above, the cap of the outer metal shell and insulating porcelain cover being removed; Fig. 4 is a section on Fig. 2 taken along the line 4—4 of said figure; Fig. 5 is an elevation of the structure shown in section in Fig. 2; and Fig. 6 is a radial axial section taken along the line 6—6 of Fig. 3.

In the drawings the porcelain socket body comprises a base member 1 and a cover member 2 held together by a bolt 3, which also serves to attach the central spring contact 4 (adapted to be pressed against by the central contact terminal of the lamp when the latter is in position); this bolt also holds, clamped against contact 4, an angled piece 5 recessed in the periphery of the base member 1, to which piece is connected, in the usual way, one of the main flexible conductors 6. A channel 7, recessed in both base and cover, is provided for this flexible conductor.

A socket shell 8, threaded as usual to receive the corresponding threaded plug terminal on the lamp, is attached to the bottom of the body member 1 by means of a bolt 9. This socket shell has a top 10 in which is formed an inwardly extended slot (shown partly dotted, Fig. 4). This slot is so shaped and its width is so determined as to

slip under over-hanging side flanges of a projection or boss 11 formed on the bottom of the body member of the shell, at the outer end of the slot, is cleared away so as to clear the outer end of boss 11. A recess in this boss receives one end of contact 4 which is thereby prevented from twisting upon the bolt 3.

A diametral slot or recess 12 extends downwardly from the top of body member 1, and serves as a slide way for the switch dog 13 (preferably made of insulating material) and for the pull chain 14, attached to said dog, by means of which said dog is actuated. Lateral grooves 15 formed in the slide way, in which wings 16 forming part of the dog are fitted, permit the dog to be moved easily.

Held by the bolt 9, in a suitable recess formed in the top of the body member 1, is a plate 17 carrying, at one side of slide way 12, a vertical spindle 18 upon which is rotatably mounted a cruciform (4 arms) switch member 19. Each of one pair of oppositely extended arms is bent upwardly and then centrally so as to constitute a U-shaped spring contact member 20, which is adapted to contact, as the switch member is rotated, with an over-hanging contact arm 21 having a downwardly bent portion recessed into the side of the body member 1 and held in position by a screw 22 which serves for attaching the end of the other main flexible conductor 23.

Each of the remaining pair of oppositely extended arms of the switch member 19 is flat; they extend at right angles to the arms 20.

An indentation is formed on the lower surface of each arm of switch member 19 and this indentation is engaged by a corresponding projection 24 formed upon the top of plate 17.

A pawl or slip member 25 has two legs 26 which rest in corresponding sockets formed in the upper part of dog 13. Springs 27 are inserted at the bottom of these sockets and below said legs and tend to push the slip member upwardly. A projection 27 on the outer leg 26 engages a corresponding projection on the socket of this leg so as to prevent the slip member being pushed upwardly too far. The forward edge 28 of member 25 is vertical and its upper surface inclines downwardly and rearwardly.

The forward end of dog 13 is provided

with a thin walled U-shaped sleeve 29, opposite walls of which are provided with circular openings and slots from the top thereof. Chain 14 is connected to the dog 13 by 5 forcing the ball at one of its ends down into the sleeve and into the circular openings.

The contact arm 21 is provided with a downward projection 30 which is adapted to drop into a corresponding hollow in the 10 U-shaped spring members 20 as these members are respectively engaged with said contact arm 21.

A spring 31 upon spindle 18 is held in position by the cover member 2 and keeps the 15 cruciform contact member 19 pressed downwardly against the plate 17.

Cover member 2, although held to the base member 1 by but a single bolt 3, is kept centered and prevented from turning by a 20 downwardly projecting lug 32, which drops into the end of slide way 12.

A spring 33 surrounds chain 14 and is interposed between dog 13 and a flange 34 at the end of slide way 12; this spring tends to 25 keep dog 13 at the end of slide way 12 opposite the chain.

An insulating sleeve 35 and outer metal shell 36 of usual type inclose the socket when assembled.

30 An incandescent lamp being in position, the operation of my invention is as follows: The parts being as shown in the figures the circuit is closed and the lamp lighted. The circuit is through conductor 6 to angled 35 piece 5 and contact 4; thence through the lamp to socket shell 8, through bolt 9 to plate 17 and spindle 18 and to switch member 19. The circuit then passes through one of the spring members 20 to and through 40 contact arm 21 and thence to conductor 23.

To break the circuit the chain 14 is pulled thus drawing the dog 13 along the slide way 12 and bringing the edge 28 of slip member 25 against the edge of that arm of 45 contact member 19 which, at the moment, lies across the slide way 12. This will cause the switch member 19 to be rotated through 90° and bring one of the flat arms of the

switch under but out of contact with the arm 21. The circuit will thus be broken. 50 On releasing the chain, the dog 13, which will have been drawn to the right (Fig. 3) so as to have a switch arm extending across the slide way behind it, will be pushed back by the spring 33; when the pawl 25 comes 55 in contact with the switch arm the pawl will be depressed against the resistance of the springs 27, so that the dog may pass the arm and rest in its original position (at the left, Fig. 3).

60 It will be noted that the socket of my invention is very simple and little liable to get out of order. It should also be noted that the pull and movement of the chain and switch dog is straight across the center of the 65 socket so that the chain is not liable to bend or kink. It should be noted, further, that each point of the circuit is separated by substantial amounts of insulation from all other parts of the circuit which differ substantially from it in E. M. F.

70 While I have described my invention in one of its possible embodiments it is obvious that other forms of the invention may easily be designed by those skilled in the art within 75 the spirit of the following claim:—

In a pull socket, an insulating body having a chamber and a transverse slideway opening from the bottom of said chamber, an insulating cover for said chamber, a spindle set in the bottom of said chamber to one side of the slideway, a cruciform switch in said chamber loosely mounted upon said spindle and adapted to have one arm cross the opening of said slideway, a spring upon 80 said spindle above the switch and having its upper end against the lower surface of the cover, a switch dog slidable in the slideway and provided with a chain, a depressible pawl upon the top of said switch dog and a 85 circuit terminal adapted to make contact with alternate switch arms, the switch being connected with the other circuit terminal.

90 In testimony whereof I have hereunto set my hand.

SAMUEL STRAUS.
